UNITED STATES PATENT OFFICE.

HARVEY S. COOK, OF VALPARAISO, INDIANA, ASSIGNOR TO COOK LABORATORIES, INC., A CORPORATION OF DELAWARE.

HYPODERMIC SYRINGE AND CARTRIDGE THEREFOR.

Original application filed March 2, 1922, Serial No. 540,628. Divided and this application filed November 25, 1925. Serial No. 71,320.

This invention relates to hypodermic syringes and cartridges therefor and is a division of my copending application Serial No. 540,628 filed March 2, 1922.

5 The invention may be understood by reference to one illustrative embodiment shown in the accompanying drawings, in which:

Fig. 1 is a longitudinal section of a cartridge embodying the invention and shown 10 inserted in a syringe; and

Fig. 2 is an enlarged section on line 2—2 of Fig. 1, but showing the position of the parts when the medicament has been discharged from the cartridge.

15 It is to be understood that the illustrative embodiment shown in the drawings is simply a preferred form of the invention; and that in the following explanation of that specific form, the described details of 20 structure and organization are merely exemplary.

Referring to the drawings, the cartridge shown is of the type employing a tubular body 3, preferably of glass, sealed at one 25 end by means of a recessed plug 4, and at the other end by a slidable plug 5, and containing a charge of medicament to be injected hypodermically. Plug 4 is conveniently made from highly resilient rubber and 30 has its recess 6 arranged axially, so that its longitudinal thickness is largely reduced, thus facilitating piercing by a canula. Plug 5 is shown as consisting of united cork and rubber sections, the rubber section being innermost for contact with the contained medicament. The cartridge exemplifies a package 35 of medicament having a pierceable end and means to reduce its interior volume to expel the medicament through a canula penetrating said pierceable end.

40 After filling of a cartridge of the described type, a bubble of air 7 is sometimes found in the cartridge. Also when piercing the cartridge with the syringe needle, if the practitioner is unskilled in the technique of using cartridge syringes, a minute bubble 45 of the air initially contained within the bore of the needle may enter the cartridge. While the empty cartridges are always sterilized immediately before filling, and the medicament itself is invariably sterile, few practitioners would care to experiment with their 50 patients or run any risks whatever; and

hence it is highly desirable to avoid the injection of any air along with the medicament. This the invention accomplishes by the simple and effective arrangement of the parts hereinafter described.

55 The syringe 8, constructed to receive the cartridge, has a head 9 forming an abutment for the pierceable end thereof and provided with a seat 10 for the enlargement 11 of a double pointed hypodermic needle 12, whose inner end pierces plug 4 when the parts are in operative position. This needle, 60 when the cartridge is not in place, may be seated and removed laterally through syringe slot 13 (Fig. 1) extending longitudinally from sight opening 14 to the extremity of the syringe, as disclosed in the parent 65 application. The cartridge itself holds the needle enlargement firmly in its seat during 70 an injection, and hence prevents movement of the needle. The illustrated needle seating and securing means is, however, not essential to the present invention.

75 To seal the needle, its inner end, in the preferred arrangement, extends sufficiently far into the cartridge-receiving chamber of the syringe so that it penetrates plug 4 and 80 projects beyond the inner edge of said plug, thus being in position to enter the slidable plug 5 and be sealed thereby, as shown in Fig. 2. As the bubble of air 7 always floats 85 on the liquid medicament (whatever the position of the syringe), it will not be expelled while plug 5 is moved through the tubular cartridge body but will be entrapped within the recess 6 when the slidable plug is moved by syringe plunger 15 against the 90 end of the recessed plug, thereby forming a closed, bubble-trapping chamber. Even if the needle is not long enough to be sealed by plug 5, any bubble of air will almost invariably be trapped within the recess 6. If 95 the air bubble is so large that part of it is likely to be ejected along with the medicament, the cartridge containing it will be rejected by the manufacturer's inspector as unfit for use. Thus danger of injecting air 100 into a patient's body is minimized. While the syringe has been described as a "hypodermic" syringe, obviously it is useful for intraosseous, intravenous and other injections.

105 A syringe cartridge or sealed medicament

package comprising a tube having sealing plugs or stoppers in its opposite ends, one to be pierced by a needle and the other to be forced inward to eject the fluid, said pierceable stopper being a recessed rubber plug of substantially the same kind, form and arrangement as the recessed pierceable plug herein shown and described, is the subject-matter of and broadly and specifically 5 claimed in my pending application filed July 1, 1921, Serial No. 481,997. A syringe comprising or embodying such a cartridge or a cartridge characterized by such a pierceable recessed stopper, with means associated 10 therewith to provide an injection-administering organization, including a removably mounted needle to pierce such recessed pierceable stopper, is subject-matter disclosed in said application Ser. No. 481,997 15 and in my pending application Serial No. 11,707 filed February 26, 1925 as a continuation of an application filed by me April 8, 1921, Serial No. 451,680½, which syringe or subject-matter is broadly and specifically 20 claimed in my said application Serial No. 11,707, the claims therefor being transferably to said application Serial No. 481,997. Therefore such a cartridge and syringe embodying the same are not claimed herein 25 broadly or otherwise than in connection with specific characteristics of the present invention as recited in the appended claims.

Moreover, a syringe embodying a cartridge-holder having a detachable rear head 30 to permit endwise insertion of the cartridge, and having a laterally-slotted front end construction substantially as herein shown and described, with a needle of the kind herein shown and described seated in said 35 front end and held seated by the cartridge, is the subject-matter of and claimed broadly and specifically in my pending application filed August 5, 1922, Serial No. 579,924, in which application the said features are 40 claimed per se and in various combinations and sub-combinations, for which reason no claim for such subject-matter or features is made herein except in connection with specific features of the present invention as 45 recited in the appended claims.

Obviously the invention is not limited to the illustrative embodiment herein disclosed.

What is claimed is:

55 1. A hypodermic syringe comprising, in combination, a syringe body having a needle seat at one end; a double ended needle having an enlargement intermediate its ends, said enlargement fitting the seat; a medicament cartridge fitting within the syringe body and having one end thereof sealed by a resilient recessed plug, the other end being closed by a resilient, slidable plug; the inner end of the needle penetrating the recessed 60 plug and projecting beyond said plug so as

to enter and be sealed by the slidable plug when the latter reaches the end of its travel through the cartridge.

2. A hypodermic syringe comprising, in combination, a syringe body; a double ended 70 needle having an enlargement; said body providing a seat at one end for the needle enlargement; a cartridge for containing medicament inserted in the syringe body and having a recessed plug sealing one end and 75 a slidable plug closing its other end; a plunger connected to the syringe body and arranged to engage the slidable plug and push the same through the cartridge; the inner end of the needle piercing the recessed 80 plug and projecting beyond the same so as to be sealed by the slidable plug as the latter reaches the end of its travel through the cartridge.

3. A hypodermic syringe comprising, in 85 combination, a syringe body; a double ended hypodermic needle; a medicament containing cartridge received within the syringe body, said cartridge being tubular and sealed 90 at its ends by resilient plugs, one of which is axially recessed and the other of which is designed to be moved through the cartridge; the syringe body and needle being made so that the inner end of the positioned needle 95 always extends the proper distance into the syringe body to pass entirely through the recessed plug and to be sealed by the movable plug as it approaches the recessed plug.

4. A medicament dispensing cartridge 100 comprising a tubular body; a resilient, recessed plug closing one end of said body; and a second resilient plug designed to seal the body at the opposite end and to slide therethrough as in the expulsion of the medicament; said second plug having its 105 inner end substantially plane and unbroken so that when pushed against the recessed plug, it forms therewith a closed chamber within which a bubble of air may be trapped.

5. A hypodermic syringe comprising, in 110 combination, a cartridge-holding body; a medicament cartridge therein comprising a tube having in its fore end a sealing plug of resilient material with an inwardly opening axial recess, and having in its opposite end a piston plug of resilient material; a cartridge-piercing canula held in operative relation to said cartridge by said body, said canula penetrating said recessed sealing plug 115 and projecting inwardly beyond the inner end of said plug; a plunger connected with the body adapted to enter said cartridge tube and push the piston plug through the cartridge tube; the construction arrangement being such that when the piston plug is forced home the inner end of the canula enters and is sealed by the piston plug while the plugs cooperate to provide a bubble-trapping chamber.

6. A syringe cartridge comprising a sealed 120

medicament container embodying a straight bored tube of glass or the like having stoppers of resilient material in its opposite ends, one of which is substantially cup-shaped 5 with its cavity facing inward, and the other of which is substantially solid or unrecessed, so that in operation a canula may be inserted through and beyond the inner end of

the recessed plug while the other plug may be forced through the tube against the recessed plug so as to seal the inner end of the canula and cooperate with the recessed plug to entrap an air bubble. ¹⁰

In testimony whereof, I have signed my name to this specification.

HARVEY S. COOK.
